SIGNALING SYSTEM

Clarence E. Lomax, Oak Park, Ill., assignor to
 Associated Electric Laboratories, Inc., Chicago,
 Ill., a corporation of Delaware

Application May 22, 1939, Serial No. 274,901

7 Claims. (Cl. 177—354)

The present invention relates to signaling systems and, more particularly, to fire alarm systems.

A fire alarm system conventionally comprises a dispatcher station or central office, a number of engine stations or houses, a plurality of alarm stations or fire boxes and a plurality of alarm lines, each of the alarm lines being arranged to connect a number of the alarm stations and at least one of the engine stations in series circuit relationship with the central office. Each alarm station is provided with a sender operative to send a signal over the associated alarm line; each of the engine stations is provided with a sender operatively connected to the associated alarm line; and the central office comprises sending apparatus operatively associated with the various alarm lines. Also, each engine station includes a receiver operatively connected to the associated alarm line; while the central office comprises receiving apparatus operatively associated with the various alarm lines. The system is so connected and arranged that an alarm may be sent over any one of the alarm lines by operating the sender at any one of the alarm stations associated with the alarm line. Furthermore, messages may be sent over any one of the alarm lines by operating the sender at any one of the engine stations associated with the alarm line and by operating the sending apparatus at the central office. Alarms and messages sent over the alarm lines are recorded by the receivers at the engine stations associated with the alarm lines and by the recording apparatus at the central office.

While a fire alarm system of the type described operates reasonably satisfactorily in service, the installation and maintenance costs thereof are greater than are desirable due primarily to the fact that it is necessary for each alarm line in the system to extend directly to the central office. Although this objection is slight when the system serves a relatively small area, it is very serious when the system serves a relatively large area.

Accordingly, it is an object of the present invention to provide in a signaling system including a central office and a plurality of stations, an improved switching arrangement for minimizing the number of lines extending directly to the central office.

Another object of the invention is to provide in a signaling system of the type described, an improved repeater arrangement for operatively interconnecting a relatively large number of

alarm lines extending to various alarm stations and a trunk line extending to a central office.

Another object of the invention is to provide in a repeater terminating a group of signal lines, an improved arrangement for receiving a signal sent over any one of the signal lines in the group and for repeating corresponding signals over the other signal lines in the group.

A further object of the invention is to provide in a repeater terminating a trunk line and two groups of signal lines, an improved arrangement adapted to receive a signal sent over the trunk line and repeat corresponding signals over the signal lines in the two groups, and to receive a signal sent over any one of the signal lines in one of the groups and repeat corresponding signals over the trunk line and over the signal lines in the other group.

A further object of the invention is to provide in a signaling system comprising a plurality of signal lines having senders associated therewith, a trunk line, a repeater operatively interconnecting the signal lines and the trunk line, and an improved arrangement incorporated in the various senders and in the repeater for preventing interference between the various senders.

A further object of the invention is to provide a signaling system adapted to serve a relatively large area divided into subareas, which utilizes an improved repeater arrangement for interconnecting signal lines disposed in the various subareas and associated with signal stations therein and trunk lines extending between the subareas and a central office.

The features of the present invention are illustrated as being incorporated in a signaling system, adapted to serve a relatively large general area divided into subareas, comprising a central office disposed at any convenient place in the general area; repeater stations disposed in the respective subareas; and engine, test and alarm stations disposed in the various subareas. A repeater is provided at each repeater station and terminates a trunk line extending to the central office. Also, each of the repeaters terminates a first group of signal or box lines and a second group of signal or combination box and alarm lines. Each of the box lines connects a number of alarm stations and at least one test station, in the subarea, in series circuit relationship with the repeater; while each of the combination box and alarm lines connects a number of alarm stations and at least one engine station, in the subarea, in series circuit relationship with the repeater. The central office comprises sending

50

55

apparatus and receiving apparatus operatively associated with the trunk lines terminating thereat; while each of the test stations and each of the engine stations comprises a sender and a receiver operatively associated with the signal line extending thereto. Finally, each of the alarm stations comprises a sender of the series non-interfering type operatively associated with the signal line extending thereto.

In accordance with one feature of the invention, each of the repeaters is so connected and arranged that it is operative to receive a signal sent over any one of the signal lines in either the first or the second groups extending thereto and repeat a corresponding signal over the trunk line extending therefrom to the central office. Also, the repeater is so connected and arranged that it is operative to receive a signal sent over the trunk line extending thereto and repeat corresponding signals over the signal lines in the first and the second groups extending therefrom. Moreover, each of the repeaters is so connected and arranged that it is operative, when a signal is sent over any one of the box lines extending thereto, to repeat corresponding signals over the combination box and alarm lines extending therefrom. Finally, each one of the repeaters is so connected and arranged that it is operative, when a signal is sent over any one of the combination box and alarm lines extending thereto, to repeat corresponding signals over the other combination box and alarm lines extending therefrom.

More particularly, the trunk line, each of the box lines and each of the combination box and alarm lines terminating at a given repeater are provided with individual line circuits. Each of the line circuits comprises an impulse relay and a timing relay, the impulse relay being provided with an operating circuit and a holding circuit. The line circuit is so connected and arranged that the operating circuit of the impulse relay is controlled in accordance with signaling impulses sent over the associated line, thereby normally to cause the impulse relay to operate intermittently. Means is provided which is controlled by the intermittent operation of any one of the impulse relays for controlling the associated one of the timing relays. Each of the timing relays is operative to effect the interruption of a point in the holding circuit of the associated impulse relay and to effect the completion of the holding circuits of the other impulse relays, thereby to prevent intermittent operation of the other impulse relays. A repeating device is included in the repeater and is controlled in accordance with the intermittent operation of the one impulse relay; and means is provided which is controlled by the one timing relay after the signaling impulses have been sent over the associated line for interrupting the holding circuits of the other impulse relays, thereby to condition the other impulse relays to be operated intermittently.

Furthermore, each of the line circuits is so connected and arranged that the operating circuit of the impulse relay therein is interrupted in the event the associated line is subjected to an open circuit fault, thereby to cause the impulse relay to remain restored. A timer is provided which is controlled in the event the impulse relay remains restored a predetermined time interval for completing the holding circuit of the impulse relay, thereby to prevent intermittent operation

thereof. Finally, the line circuit comprises means controlled when the line associated therewith is recompleted for interrupting the holding circuit of the impulse relay, thereby to recondition the impulse relay to be operated intermittently.

In accordance with a further feature of the invention, each of the repeaters comprises normally effective control means for rendering the repeater controllable over the trunk line or any one of the signal lines terminating thereat, means governed when the repeater is rendered controllable over the trunk line or any one of the signal lines terminating thereat for rendering ineffective the control means, and means controlled after the signal has been sent over the trunk line or the one signal line terminating thereat for rendering again effective the control means. The sender at each of the alarm stations comprises normally effective means for sending a signal over the associated signal line and means governed when a signal is being sent over the associated signal line for rendering ineffective the last-mentioned means. The connection and arrangement of the repeater in conjunction with the type of sender utilized at each of the alarm stations positively prevents interference between the senders and interference with the repeater when the repeater is busy.

Further features of the invention pertain to the particular arrangement of the circuit elements of the signaling system whereby the above-outlined and additional features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings, in which Figures 1 to 3, inclusive, taken together, illustrate diagrammatically the details of a signaling system having incorporated therein the present invention.

Referring now more particularly to Figs. 1 to 3, inclusive, of the drawings, the signaling system there illustrated comprises a central office 50, a number of repeater stations, including the repeater station 60, and a number of alarm trunks respectively extending between the central office and the repeater stations, including the alarm trunk 301 extending between the central office 50 and the repeater station 60. Each of the repeater stations is provided with a repeater; and a group of box lines and a group of combination box and alarm lines terminate at each of the repeater stations. For example, the repeater station 60 is provided with the repeater 200; the group of box lines terminating at the repeater station 60 includes the box line 109; and the group of combination box and alarm lines terminating at the repeater station 60 includes the combination box and alarm lines 115 and 250.

Each of the box lines is of the series type and connects a test station and a plurality of alarm stations or fire boxes in series circuit relationship. For example, the series box line 109 connects the test station 10 and the fire boxes 103, 104, 105, etc., in series circuit relationship. Also, each of the combination box and alarm lines is of the series type and connects a plurality of engine stations and a plurality of alarm stations or fire boxes in series circuit relationship. For

example, the series combination box and alarm line 115 connects the engine stations 75, 80, etc., and the fire boxes 104, 109, 120, etc., in series circuit relationship. The alarm trunk, each of the box lines, and each of the combination box and alarm lines terminating at a given repeater station are provided with line circuits individual thereto at the repeater station, which line circuits are operatively associated with the repeater thereat, the alarm trunk 301, the box line 100 and the combination box and alarm lines 115 and 260 terminating at the repeater station 60 being respectively provided with the line circuits 320, 130, 160 and 265 individual thereto at the repeater station 60, which line circuits are operatively associated with the repeater 200 thereat.

Preferably, the signaling system serves a general area divided into a plurality of subareas. The central office 50 is disposed at a convenient place in the general area; while the repeater stations are respectively disposed in the various subareas, the repeater station 60 being disposed in a particular subarea. Furthermore, the test station 70, etc., the engine stations 75, 80, etc., and the alarm stations 103, 104, 105, 118, 119, 120, etc., are disposed in the particular subarea wherein the repeater station 60 is disposed.

The central office 50 comprises a recorder or printer and a sending key individually associated with each alarm trunk terminating thereat, the printer P310 and the sending key K306 at the central office 50, shown on the right-hand side of Fig. 3, being individually associated with the alarm trunk 301 terminating thereat. Each of the test stations comprises a recorder or printer and a sending key associated with the box line extending thereto, the printer P110 and the sending key K108 at the test station 70, shown on the left-hand side of Fig. 1, being individually associated with the box line 100 extending to the test station 70. Also, each of the engine station comprises a recorder or printer and a sending key associated with the combination box and alarm line extending thereto, the printer P126 and the sending key K125 at the engine station 75, shown on the left-hand side of Fig. 1, being associated with the combination box and alarm line 115 extending to the engine station 75. It is noted that each of the engine stations is provided with the usual fire-fighting apparatus; while each of the test stations may be provided with some fire-fighting apparatus. Furthermore, a central dispatcher or fire marshal supervises the apparatus at the central office and coordinates the activities of the various engine and test stations.

Each of the fire boxes, such, for example, as the fire box 104, shown on the left-hand side of Fig. 1, is of the well-known series non-interfering type and is so constructed and arranged that when the operating lever thereat is operated, the fire box ordinarily operates immediately and automatically to transmit over the associated line, a number of times, a code corresponding to the particular fire box. Furthermore, the fire box is so connected and arranged that it does not operate immediately to transmit in the event that the associated line is busy, but delays the transmission until the associated line becomes idle.

Preferably, the repeater at each of the repeater stations is connected and arranged in the manner of the repeater 200 at the repeater station 60, which comprises, as shown in Fig. 2, conventional timing apparatus TA265, a start relay

R210, a first impulse relay R220, a second impulse relay R230, a test relay R240 and a control relay R250. Preferably, the line circuits at each of the repeater stations are connected and arranged in an identical manner. For example, the line circuit 130 at the repeater station 60 and individually associated with the box line 100 comprises, as shown on the right-hand side of Fig. 1, a lockout relay R135, a line relay R140, an impulse relay R145, a timing relay R150 and a control relay R155; the line circuit 160 at the repeater station 60 and individually associated with the combination box and alarm line 115 comprises, as shown on the right-hand side of Fig. 1, a lockout relay R165, a line relay R170, an impulse relay R175, a timing relay R180 and a control relay R185; and the line circuit 320 at the repeater station 60 and individually associated with the alarm trunk 301 comprises, as shown on the left-hand side of Fig. 3, a control relay R330, a timing relay R335, an impulse relay R340, a line relay R345 and a lockout relay R350.

The connection and arrangement of the signaling system will best be understood from a consideration of the description of the operation thereof appearing hereinafter.

The alarm trunk 301 is included in a normally completed series circuit extending from one terminal of the battery 360 by way of C304, the winding of the printer magnet PM311 of the printer P310 at the central office 50, the sending key K306 at the central office 50, C305, the winding of the line relay R345, C362, RA225 and C361 to the other terminal of the battery 360. The box line 100 is included in a normally completed series circuit extending from one terminal of the battery 137 by way of C190, RA221 and the multiple connected strap S227, RA230, C191, the winding of the line relay R140, C102, the sending key K108 at the test station 70, the winding of the printer magnet PM111 of the printer P110 at the test station 70, the fire boxes 105, 104, 103, etc., and C101 to the other terminal of the battery 137. The combination box and alarm line 115 is included in a normally completed series circuit extending from one terminal of the battery 167 by way of C192, RA224, RA232, C193, the winding of the line relay R170, C111, the sending key K125 at the engine station 75, the winding of the printer magnet PM127 of the printer P126 at the engine station 75, the fire boxes 120, 119, 118, etc., apparatus in the engine station 80, and C116 to the other terminal of the battery 167.

Accordingly, the line relay R345 in the line circuit 320 individually associated with the alarm trunk 301 normally occupies its operated position, thereby to retain completed, at RA346 and RC347, an obvious circuit for energizing the lower winding of the impulse relay R340 in order to retain the last-mentioned relay in its operated position. Also, the line relay R140 in the line circuit 130 individually associated with the box line 100 normally occupies its operated position, thereby to retain completed, at RA141 and RC142, an obvious circuit for energizing the lower winding of the impulse relay R145 in order to retain the last-mentioned relay in its operated position. Similarly, the line relay R170 in the line circuit 160 individually associated with the combination box and alarm line 115 normally occupies its operated position, thereby to retain completed, at RA171 and RC172, an obvious circuit for energizing the lower winding of the impulse relay

R175 in order to retain the last-mentioned relay in its operated position.

In order to initiate an alarm on one of the box lines, such as the box line 100, the operating lever at one of the fire boxes included in the line, such as the operating lever of the fire box 104 included in the box line 100, is operated. In the event the box line 100 is idle at this time, when the operating lever of the fire box 104 is operated, the fire box 104 operates immediately to transmit, a number of times, a code individually corresponding to the fire box 104, this code including a number of digits, each including one or more impulses. On the other hand, in the event the box line 100 is busy at this time, when the operating lever of the fire box 104 is operated, the fire box 104 does not operate immediately to transmit the code but delays the transmission of the code until the box line 100 becomes idle. In transmitting the code, the fire box 104 first interrupts at the switch S107 the previously traced series circuit including the box line 100, thereby to cause the line relay R140 in the line circuit 130 individually associated with the box line 100 to restore. Upon restoring, the line relay R140 interrupts, at RA141 and RC142, a point in the previously mentioned circuit for energizing the lower winding of the impulse relay R145 and prepares, at RA141 and RC143, a point in a holding circuit, traced hereinafter, for energizing the upper winding of the lockout relay R135 in series with the lower winding of the impulse relay R145. When the previously mentioned circuit for energizing the lower winding of the impulse relay R145 is interrupted, the last-mentioned relay restores, thereby to interrupt, at RA146, a point in a holding circuit, traced hereinafter, for energizing the upper winding thereof, to prepare, at RA148, a circuit, traced hereinafter, for energizing the winding of the first impulse relay R220 in the repeater 200, and to complete, at RA147, an obvious circuit for energizing the winding of the timing relay R150. When the winding of the timing relay R150 is thus energized, this relay operates, thereby to complete, at RA153 and RC152, RC151, an obvious circuit for energizing the winding of the control relay R155, thereby to cause the latter relay to operate.

Upon operating, the control relay R155 completes, at RA155, a holding circuit for energizing the winding thereof, this circuit extending from ground by way of RA153, RC152, RA155 and the winding of R155 to battery. Also, upon operating, the control relay R155 completes, at RA156, a connection between the conductors C190 and C191 of the box line 100, thereby to short-circuit the portion of the box line 100 extending into the repeater 200. It is noted that the portion of the box line 100 extending into the repeater 200 is short-circuited, thereby positively to prevent the operation of the repeater from causing impulses to be transmitted from the repeater 200 back over the box line 100. Furthermore, the control relay R155 interrupts, at RA157, a point in a holding circuit, traced hereinafter, for energizing the upper winding of the impulse relay R145, prepares, at RA158, a further point in the previously mentioned circuit for energizing the winding of the first impulse relay R220 in the repeater 200, and completes, at RA159, an obvious circuit for energizing the winding of the start relay R210 in the repeater 200, thereby to cause the last-mentioned relay to operate.

Upon operating, the start relay R210 com-

pletes, at RA214, a holding circuit for energizing the upper winding of the impulse relay R175 in the line circuit 160 individually associated with the combination box and alarm line 115, this circuit extending from ground by way of RA214, C161, RA187, RA176 and the upper winding of R175 to battery. Also, the start relay R210 completes, at RA215, a holding circuit for energizing the upper winding of the impulse relay R340 in the line circuit 320 individually associated with the alarm trunk 301, this circuit extending from ground by way of RA215, C363, RA334, RA342 and the upper winding of R340 to battery. Similarly, the start relay R219 completes, at RA216, etc., holding circuits for respectively energizing the upper windings of the start relays in the line circuits 265, etc., individually associated with the combination box and alarm lines 269, etc. Accordingly, at this time, the box line 100 has seized the repeater 200 and the start relay R210 in the repeater 200 has operated to complete holding circuits for retaining the impulse relays in the line circuits individually associated with the other box lines, the combination box and alarm lines and the alarm trunk associated with the repeater 200 in their operated positions.

Also, upon operating, the start relay R210 completes, at RA213, the previously mentioned circuit for energizing the winding of the first impulse relay R220, this circuit extending from ground by way of RA148, RA158, C132, RA213 and the winding of R220 to battery. When energized over the above-traced circuit, the first impulse relay R220 operates, thereby to interrupt, at RA224, a point in the previously traced series circuit including the combination box and alarm line 115, to interrupt, at RA226, etc., points in the previously traced series circuits including the combination box and alarm line 260, etc., and to interrupt, at RA225, a point in the previously traced series circuit including the alarm trunk 301. Furthermore, it is noted that the first impulse relay R220 interrupts, at the contacts RA221 and at similar contact points, the series circuits including the box line 100 and the other box lines. However, this operation of the contacts RA221 and the corresponding contacts is without effect in view of the fact that the contacts RA221 are short-circuited by the strap S227 and the corresponding contacts are short-circuited by corresponding straps in a similar manner.

In view of the above description of the box line 100 and the combination box and alarm line 115, it will be apparent that the box line 100 may be readily converted into a combination box and alarm line merely by cutting the strap S227 and that the combination box and alarm line 115 may be readily converted into a box line merely by adding a strap short-circuiting the contacts RA224 included in series circuit relation therewith.

From the foregoing it is apparent that the operation of the first impulse relay R220 in the repeater 200 interrupts the series circuits including the alarm trunk 301 and each of the combination box and alarm lines associated with the repeater 200; however, it does not interrupt the series circuits including the box lines. Thus, it will be apparent that the operation of the start relay R210 in the repeater 200 has the effect of rendering the alarm trunk 301, each of the box lines, and each of the combination box and alarm lines busy; while the operation of the first impulse relay R220 in the repeater 200 has the effect of re-

peating the code received from the fire box 104 by way of the box line 100 over the alarm trunk 301 and each of the combination box and alarm lines.

Continuing now with the operation of the apparatus included in the signaling system incident to the interruption of the previously traced series circuit including the box line 100, when this series circuit is interrupted, the circuit for energizing the winding of the printing magnet PM111 of the printer P110 at the test station 70 is interrupted, thereby to cause the printer magnet PM111 to restore. When the printer magnet PM111 restores, the armature PA112 thereof is released, thereby to cause the stylus operatively associated with the armature PA112 to mark the associated moving tape 113. When the previously traced series circuit including the alarm trunk 301 is interrupted, the circuit for energizing the winding of the printer magnet PM311 of the printer 310 at the central office 50 is interrupted, thereby to cause the printer magnet PM311 to restore. Upon restoring, the printer magnet PM311 releases its armature PA312, thereby to cause the stylus operatively associated with the armature PA312 to mark the associated moving tape 313. Also, when the previously traced series circuit including the combination box and alarm line 115 is interrupted, the circuit for energizing the winding of the printer magnet PM127 of the printer P126 at the engine station 75 is interrupted, thereby to cause the printer magnet PM127 to restore. When the printer magnet PM127 restores, it releases its armature PA128, thereby to cause the stylus operatively associated with the armature PA128 to mark the associated moving tape 129.

The fire box 104 then operates to complete at the switch S107 the previously traced series circuit including the box line 100, thereby to cause the line relay R140 in the line circuit 130 individually associated with the box line 100 to re-operate. When the line relay R140 reoperates, it completes, at RA141 and RC142, the previously mentioned circuit for energizing the lower winding of the impulse relay R145, thereby to cause the last-mentioned relay to reoperate. When the impulse relay R145 reoperates, it interrupts, at RA147, the previously mentioned circuit for energizing the winding of the timing relay R150, thereby to cause the latter relay to restore. When the timing relay R150 restores, it sets the weighted armature RA153 thereof into vibration, whereupon the weighted armature RA153 alternately engages the associated contacts C152 and C154 in order to complete intermittently the previously traced holding circuit for energizing the winding of the control relay R155. The control relay R155, being of the slow-to-release type, does not restore due to the fact that the previously traced holding circuit for energizing the winding thereof is intermittently completed. Furthermore, upon reoperating, the impulse relay R145 interrupts, at RA148, the previously traced circuit for energizing the winding of the first impulse relay R220 in the repeater 200, thereby to cause the last-mentioned relay to restore. Upon restoring, the first impulse relay R220 recompletes, at RA224, the previously traced series circuit including the combination box and alarm line 115, recompletes at RA225, the previously traced series circuit including the alarm trunk 301, and recompletes, at RA226, etc., the series circuits including the combination box and alarm lines 260, etc.

When the previously traced circuit including

the box line 100 is recompleted, the printer magnet PM111 of the printer P110 at the test station 70 reoperates, thereby to cause the stylus operatively associated with the armature PA110 to disengage the associated moving tape 113. Also, when the previously traced series circuit including the combination box and alarm line 115 is recompleted, the printer magnet PM127 of the printer P126 at the engine station 75 reoperates, thereby to cause the stylus operatively associated with the armature PA128 to disengage the associated moving tape 129. Similarly, when the previously traced series circuit including the alarm trunk 301 is recompleted, the printer magnet PM311 of the printer 310 at the central office 50 reoperates, thereby to cause the stylus operatively associated with the armature PA312 to disengage the associated moving tape 313.

It is noted that the line relay R140 in the line circuit 130 individually associated with the box line 100 follows the impulses of the digits comprising the code transmitted from the fire box 104 over the box line 100, this relay operating each time the previously traced series circuit including the box line 100 is completed, and this relay restoring each time this series circuit including the box line 100 is interrupted. The line relay R140 follows the impulses transmitted over the previously traced series circuit including the box line 100 and repeats these impulses to the impulse relay R145, which last-mentioned relay repeats these impulses to the first impulse relay R220 in the repeater 200. The first impulse relay R220 in the repeater 200 repeats the impulses over the alarm trunk 301 and over each of the combination box and alarm lines in the previously described manner. Accordingly, the printer P110 at the test station 70 included in the box line 100, the printer P310 at the central office 50 included in the alarm trunk 301, the printer P126 at the engine station 75 included in the combination box and alarm line 115, and the other printers at the engine stations included in the other combination box and alarm lines operate to record the code transmitted, a number of times, from the particular fire box 104. Furthermore, it is noted that while the code is being transmitted, a number of times, from the fire box 104, the control relay R155 in the line circuit 130 individually associated with the box line 100 remains in its operated position, thereby to cause the start relay R210 in the repeater 200 to remain in its operated position. The operated start relay R210 in the repeater 200 retains the impulse relays in the line circuits individually associated with the alarm trunk 301, the combination box and alarm lines, and the other box lines, with the exception of the box line 100 upon which the alarm is initiated, in their operated positions, thereby effectively to retain busy the alarm trunk 301, each of the combination box and alarm lines and each of the box lines.

After the fire box 104 has operated to transmit the corresponding code, a number of times, over the previously traced series circuit including the box line 100, operation thereof is arrested and the previously traced series circuit including the box line 100 is recompleted, thereby to arrest further operation of the line relay R140 in the line circuit 130 individually associated with the box line 100. When the operation of the line relay R140 is arrested, the operation of the impulse relay R145 and the timing relay R150 is arrested. Shortly thereafter, the weighted armature RA153

of the timing relay R150 assumes a position of rest disposed intermediate the associated contacts RC152 and RC154, thereby to interrupt the previously traced holding circuit for energizing the winding of the control relay R155. Shortly thereafter, the control relay R155 restores to complete, at RA157, the previously mentioned holding circuit for energizing the upper winding of the impulse relay R145, this circuit extending from ground by way of RA211, C181, RA157, RA146 and the upper winding of R145 to battery. Also, the control relay R155 interrupts, at RA159, the previously mentioned circuit for energizing the start relay R210 in the repeater 200 in order to cause the last-mentioned relay to restore. Upon restoring, the start relay R210 interrupts, at RA214, the previously traced holding circuit for energizing the upper winding of the impulse relay R175 in the line circuit 160 individually associated with the combination box and alarm line 115, interrupts, at RA215, the previously traced holding circuit for energizing the upper winding of the impulse relay R340 in the line circuit 320 individually associated with the alarm trunk 301, and interrupts, at RA216, etc., the holding circuits for energizing the upper windings of the impulse relays in the line circuits 265, etc., individually associated with the combination box and alarm lines 260, etc. Also, the start relay R210 interrupts, at RA211, the previously traced holding circuit for energizing the upper winding of the impulse relay R145 in the line circuit 130 individually associated with the box line 100 and interrupts the other holding circuits for energizing the upper windings of the impulse relays in the line circuits individually associated with the other box lines.

Furthermore, when the control relay R155 restores, it interrupts, at RA155, a further point in the previously traced holding circuit for energizing the winding thereof, interrupts, at RA158, a further point in the previously traced circuit for energizing the winding of the first impulse relay R220 in the repeater 200, and interrupts, at RA156, the previously mentioned path for short-circuiting the portion of the box line 100 extending into the repeater 200.

At this time, the repeater 200, the alarm trunk 301, each of the box lines and each of the combination box and alarm lines are idle and available for further use.

In view of the foregoing description of the manner in which an alarm is initiated at the fire box 104 on the box line 100, it will be understood that an alarm may be initiated at any one of the fire boxes on the associated box or combination box and alarm line and that the code transmitted over the associated line to the repeater 200 will be repeated thereby over the alarm trunk 301 and over each of the combination box and alarm lines, but not over the box lines, as previously explained. Specifically, it will be understood that when an alarm is initiated at the fire box 119 on the combination box and alarm line 115, the line circuit 160 individually associated with the combination box and alarm line 115 will operate in a manner similar to the operation of the line circuit 130 individually associated with the box line 110, as previously explained, thereby to cause the repeater 200 to repeat the code over the alarm trunk 301 and over each of the other combination box and alarm lines.

Furthermore, it will be understood that an

alarm or other message may be transmitted from the test station 70 over the box line 100 by operating the sending key K108 at the test station 70 and that this alarm or message will be repeated by the repeater 200 in the previously described manner over the alarm trunk 301 and over each of the combination box and alarm lines, but will not be repeated over the box lines. Similarly, it will be understood that an alarm or other message may be transmitted from the engine station 75 over the combination box and alarm line 115 by operating the sending key K125 at the engine station 75 and that this alarm or message will be repeated by the repeater 200 in the previously described manner over the alarm trunk 301 and over each of the other combination box and alarm lines, but will not be repeated over the box lines.

Instructions may be transmitted from the central office 50 over the alarm trunk 301 to the repeater 200 by operating the sending key K306 at the central office 50 and repeated by the repeater 200 over each of the box lines and over each of the combination box and alarm lines terminating at the repeater 200. More specifically, the sending key K306 at the central office 50 is operated, thereby to interrupt and to complete alternately the previously traced series circuit including the alarm trunk 301. Each time the previously traced series circuit including the alarm trunk 301 is interrupted, the circuit for energizing the winding of the line relay R345 in the line circuit 320 individually associated with the alarm trunk 301 is interrupted, thereby to cause the last-mentioned relay to restore. Upon restoring, the line relay R345 interrupts, at RA346 and RC347, the previously mentioned circuit for energizing the lower winding of the impulse relay R340, thereby to cause the last-mentioned relay to restore. Upon restoring, the impulse relay R340 prepares, at RA341, a circuit, traced hereinafter, for energizing the second impulse relay R230 in the repeater 200, interrupts, at RA342, a point in a holding circuit, traced hereinafter, for energizing the upper winding thereof, and completes, at RA343, an obvious circuit for energizing the winding of the timing relay R335. When the winding of the timing relay R335 is thus energized, this relay operates to complete, at RA338 and RC337, RC336, a circuit for energizing the winding of the control relay R330, this circuit extending from ground by way of RA338, RC337, RC336 and the winding of R330 to battery. When energized over the above-traced circuit, the control relay R330 operates to complete, at RA339, a holding circuit for energizing the winding thereof, this circuit extending from ground by way of RA338, RC337, RA339 and the winding of R330 to battery. Also, the control relay R330 prepares, at RA331, a further point in the previously mentioned circuit for energizing the winding of the second impulse relay R230 in the repeater 200, interrupts, at RA334, a point in the previously traced holding circuit for energizing the upper winding of the impulse relay R340, completes, at RA333, an obvious path for short-circuiting the portion of the alarm trunk 301 extending into the repeater 200, and completes, at RA332, an obvious circuit for energizing the winding of the start relay R210 in the repeater 200, thereby to cause the last-mentioned relay to operate.

Upon operating, the start relay R210 completes, at RA211, the previously traced holding circuit for energizing the upper winding of the impulse

relay R145 included in the line circuit 130 individually associated with the box line 100, completes holding circuits for energizing the upper windings of the impulse relays in the line circuits individually associated with the other box lines, completes, at RA214, the previously traced circuit for energizing the upper winding of the impulse relay R175 in the line circuit 160 individually associated with the combination box and alarm line 115, prepares, at RA215, a point in the previously traced holding circuit for energizing the upper winding of the impulse relay R340 in the line circuit 320 individually associated with the alarm trunk 301, and completes, at RA216, etc., the holding circuits for energizing the windings of the impulse relays in the line circuit 265, etc., individually associated with the combination box and alarm lines 260, etc. At this time the impulse relays included in the line circuits individually associated with the box lines and with the combination box and alarm lines are retained in their operated positions, thereby effectively to maintain the box lines and the combination box and alarm lines busy as previously explained.

Also, upon operating, the start relay R210 completes, at RA212, the previously mentioned circuit for energizing the second impulse relay R230, this circuit extending from ground by way of RA341, RA331, C365, RA212 and the winding of R230 to battery. When energized over the above-traced circuit, the second impulse relay R230 operates to interrupt, at RA230, the previously traced series circuit including the box line 100, to interrupt the series circuits including the other box lines, to interrupt, at RA232, the previously traced series circuit including the combination box and alarm line 115, and to interrupt, at RA233, etc., the series circuits including the other combination box and alarm lines 260, etc.

When the previously traced series circuit including the box line 100 is interrupted, the printer P10 at the test station 70 included in the box line 100 operates as previously explained. Also when the previously traced series circuit including the combination box and alarm line 115 is interrupted, the printer P125 and the engine station 75 operates as previously explained. In a similar manner, the printers at the other test stations included in the box lines and the printers at the other engine stations included in the other combination and alarm lines are operated. Also, when the previously traced series circuit including the alarm trunk 301 is interrupted at the sending key K306, the printer P310 at the central office 50 operates as previously explained.

When the sending key K306 is returned to its normal position, the previously traced series circuit including the alarm trunk 301 is recompleted, thereby to cause the line relay R345 in the line circuit 320 individually associated with the alarm trunk 301 to reoperate. Upon reoperating, the line relay R345 recompletes, at RA346 and RC347, the previously mentioned circuit for energizing the lower winding of the impulse relay R340, thereby to cause the latter relay to reoperate. Upon reoperating, the impulse relay R340 interrupts, at RA341, the previously traced circuit for energizing the winding of the second impulse relay R230 in the repeater 200, thereby to cause the latter relay to restore. Upon restoring, the second impulse relay R230 completes, at RA230, the previously traced series circuit including the box line 100, completes the series circuits in-

cluding the other box lines, completes, at RA232, the previously traced series circuit including the combination box and alarm line 115, and completes, at RA233, etc., the series circuits including the other combination box and alarm lines 260, etc. In view of the foregoing description, it will be apparent that the printers at the test stations and at the engine stations respectively associated with the box lines and with the combination box and alarm lines operate to record the message transmitted from the central office 50 by operating the sending key K306.

At the conclusion of the message transmitted from the central office 50, the sending key K306 is returned to its normal position, thereby to cause the line relay R345 in the line circuit 320 individually associated with the alarm trunk 301 to remain in its operated position. The line circuit 320 then operates in a manner similar to the operation of the line circuit 130 previously described, thereby to cause the control relay R330 to restore. Upon restoring, the control relay R330 interrupts, at RA330, the previously traced holding circuit for energizing the winding thereof, completes, at RA334, the previously traced holding circuit for energizing the upper winding of the impulse relay R340, interrupts, at RA333, the previously mentioned path for short-circuiting the portion of the alarm trunk 301 extending into the repeater 200, interrupts, at RA332, the previously mentioned circuit for energizing the winding of the start relay R210 in the repeater 200, and interrupts, at RA331, a further point in the previously traced circuit for energizing the winding of the second impulse relay R230 in the repeater 200. The start relay R210 and the second impulse relay R230 then restores, thereby to render the repeater 200, the alarm trunk 301, each of the box lines and each of the combination box and alarm lines idle as previously explained.

In view of the foregoing description of the operation of the signaling system, it will be understood that when the alarm trunk 301 is interrupted, the repeater 200 is seized by the alarm trunk 301 and is rendered busy to each of the box lines and each of the combination box and alarm lines; and the repeater 200 is rendered effective to transmit impulses received by way of the alarm trunk 301 over each of the box lines and over each of the combination box and alarm lines. When one of the box lines, such as the box line 100, is interrupted, the repeater 200 is seized by the box line 100 and is rendered busy to the alarm trunk 301, each of the other box lines and each of the combination box and alarm lines; and the repeater 200 is rendered effective to transmit impulses received by way of the box line 100 over the alarm trunk 301 and over each of the combination box and alarm lines. When one of the combination box and alarm lines, such as the combination box and alarm line 115, is interrupted, the repeater 200 is seized by the combination box and alarm line 115 and is rendered busy to the alarm trunk 301, each of the other combination box and alarm lines and each of the box lines; and the repeater 200 is rendered effective to transmit impulses received by way of the combination box and alarm line 115 over the alarm trunk 301 and over each of the other combination box and alarm lines.

Furthermore, it is noted that when the repeater 200 is seized by the alarm trunk 301, the fire boxes associated with the box lines and with the combination box and alarm lines are rendered busy due to the fact that the repeater 200

operates at this time to repeat impulses over the box lines and over the combination box and alarm lines. Also, when the repeater 200 is seized by one of the box lines at a given one of the fire boxes associated therewith, the other of the fire boxes associated with the one box line and the fire boxes associated with the combination box and alarm lines are rendered busy due to the fact that the given fire box sends impulses over the one box line and the repeater 200 operates at this time to repeat impulses over the combination box and alarm lines. However, the fire boxes associated with the other box lines are not rendered busy due to the fact that the repeater 200 does not repeat impulses at this time over the other box lines. Accordingly, at this time, the fire boxes associated with the other box lines may be operated in order to cause the printers at the test stations associated therewith to operate as previously explained. Similarly, when the repeater 200 is seized by one of the combination box and alarm lines at a given one of the fire boxes associated therewith, the other of the fire boxes associated with the one combination box and alarm line and the fire boxes associated with the other of the combination box and alarm lines are rendered busy due to the fact that the given fire box sends impulses over the one combination box and alarm line and the repeater 200 operates at this time to repeat impulses over the other of the combination box and alarm lines. However, the fire boxes associated with the box lines are not rendered busy due to the fact that the repeater 200 does not repeat impulses at this time over the box lines. Accordingly, at this time the fire boxes associated with the box lines may be operated in order to cause the printers at the test stations associated therewith to operate as previously explained.

In order to prevent sustained false seizure of the repeater 200 due to the failure of one of the box lines, one of the combination box and alarm lines, or the alarm trunk 301 caused by an open circuit fault thereon, an arrangement is incorporated in the repeater 200 and the line circuits individually associated with the various box lines, combination box and alarm lines and the alarm trunk 301. This arrangement comprises the test relay R240 and the control relay R250 in the repeater 200 and the lockout relays in the various line circuits.

In the event one of the box lines, such as the box line 100, is accidentally interrupted, an alarm is first initiated on the box line 100 as previously explained, thereby to cause the start relay R210 and the first impulse relay R220 in the repeater 200 to operate. In this case, the first impulse relay R220 in the repeater 200 remains in its operated position and does not alternately restore and reoperate in the usual manner due to the fact that no impulses are being transmitted over the box line 100. Upon operating, the first start relay R220 completes, at RA222, a path for applying battery potential to the control conductor P1, this path extending from battery potential by way of the upper winding of R240 and RA222 to the control conductor P1. This application of battery potential to the control conductor P1 initiates the operation of timing apparatus TA265 which causes ground potential to be applied to the control conductor P1 after a predetermined time interval, thereby to complete a circuit for energizing the upper winding of the test relay R240, whereupon the test relay

R240 operates. Upon operating, the test relay R240 completes, at RA241, a holding circuit for energizing the lower winding thereof, this circuit extending from ground by way of RA223, RA241 and the lower winding of R240 to battery. Also, upon operating, the test relay R240 prepares, at RA242, a circuit for energizing the winding of the control relay R250, which circuit being completed automatically in the event the timing apparatus TA265 associated with the control conductor P1 is retained in its operated position for a predetermined time interval. In the last-mentioned event, ground potential is applied in the timing apparatus TA265 to the control conductor P2, thereby to complete the previously mentioned circuit for energizing the winding of the control relay R250, this circuit extending from the grounded control conductor P2 by way of RA242 and the winding of R250 to battery. When energized over the above-traced circuit, the control relay R250 operates to complete, at RA251, obvious multiple circuits for energizing the lower windings of the lockout relays in the various line circuits, thereby to cause the last-mentioned relays in the various line circuits to operate.

When the lockout relay R135 in the line circuit 130 individually associated with the box line 100 operates, it completes, at RA136, the previously mentioned holding circuit for energizing in series the upper winding of the lockout relay R135 and the lower winding of the impulse relay R145, this circuit extending from ground by way of RA141, RC143, the upper winding of R135, RA136 and the lower winding of RA145 to battery. When energized over the above-traced circuit, the impulse relay R145 re-operates, thereby to cause the timing relay R150 and the control relay R155 to restore as previously explained. When the timing relay R150 and the control relay R155 in the line circuit 130 restore, the previously traced circuits for energizing the start relay R210 and the first impulse relay R220 in the repeater 200 are interrupted, thereby to cause the relays to restore as previously explained. Upon restoring, the first impulse relay R220 interrupts, at RA222, the previously traced path for applying battery potential to the control conductor P1, thereby to cause the operation of the timing apparatus TA265 associated with the control conductor P1 to be arrested and to interrupt the previously traced circuit for energizing the upper winding of the test relay R240. Also, upon restoring, the first impulse relay R220 interrupts, at RA223, the previously traced holding circuit for energizing the lower winding of the test relay R240. The test relay R240 then restores to interrupt, at RA242, the previously traced circuit for energizing the winding of the control relay R250, whereupon the latter relay restores. Upon restoring, the control relay R250 interrupts, at RA251, the previously mentioned multiple circuits for energizing the lower windings of the lockout relays in the various line circuits.

It is noted that, upon operating, only the lockout relay R135 in the line circuit 130 individually associated with the faulty box line 100 completes a holding circuit for energizing the upper winding thereof in series with the lower winding of the associated impulse relay, due to the fact that only the associated line relay R140 occupies its restored position at this time. For example, when the lockout relay R165 in the line circuit 160 individually associated with the combination

box and alarm line 115 operates, it does not complete at RA166 a holding circuit for energizing the upper winding thereof in series with the lower winding of the impulse relay R175, due to the fact that the associated line relay R170 occupies its operated position, thereby to retain interrupted, at RA171 and RC173, a point in the previously mentioned holding circuit for energizing the upper winding of the lockout relay R165 in series with the lower winding of the impulse relay R175. Accordingly, when the control relay R250 in the repeater 200 restores to interrupt, at RA251, the previously mentioned multiple circuits for energizing the lower windings of the lockout relays in the various line circuits, all of the lockout relays restore, with the exception of the lockout relay R135 in the line circuit 130 individually associated with the faulty box line 100. At this time the faulty box line 100 is locked out of service by the operated lockout relay R135 in the associated line circuit 130; and the repeater 200, the remainder of the box lines, the combination box and alarm lines and the alarm trunk 301 are idle and available for further use.

It is noted that the faulty box line 100 will remain locked out of service until it is repaired, at which time the previously traced series circuit including the box line 100 will be recompleted, thereby to cause the line relay R140 in the line circuit 130 individually associated with the box line 100 to reoperate. When the line relay R140 reoperates, it interrupts, at RA141 and RC143, the previously traced holding circuit for energizing the upper winding of the lockout relay R135 in series with the lower winding of the impulse relay R145 and completes, at RA141 and RC142, the previously mentioned original circuit for energizing the lower winding of the impulse relay R145, whereupon the lockout relay R135 restores and the impulse relay R145 remains in its operated position.

In view of the foregoing description of the operation of the arrangement for locking the faulty box line 100 out of service, it will be understood that other faulty box lines or any one of the combination box and alarm lines which is faulty will be locked out of service by the operation of the arrangement in a similar manner.

Furthermore, it is noted that this arrangement is so connected and arranged that the alarm trunk 301 may be locked out of service in the event that it fails due to an open circuit fault thereon. In the event that the alarm trunk 301 is interrupted, the line circuit 320 individually associated therewith operates, in the previously described manner, thereby to cause the start relay R210 and the second impulse relay R230 in the repeater 200 to operate as previously explained. Upon operating, the second impulse relay R230 completes, at RA234, an alternative path for applying battery potential to the control conductor P1, this path extending from battery by way of the upper winding of the timing relay R240 and RA234 to the control conductor P1. Furthermore, the second impulse relay R230 prepares, at RA235, an alternative holding circuit for energizing the lower winding of the test relay R240. Under these conditions, the second impulse relay R230 does not alternately operate and restore due to the fact that no impulses are being transmitted over the alarm trunk 301. Accordingly, the timing apparatus TA265 associated

with the control conductor P1 operates after a predetermined time interval, thereby to complete an alternative circuit for energizing the upper winding of the test relay R240. This circuit 5 extends from ground potential appearing upon the control conductor P1 by way of RA234 and the upper winding of R240 to battery. When energized over the above-traced circuit, the test relay R240 operates to complete, at RA241, the previously mentioned alternative holding circuit for energizing the lower winding thereof, this circuit extending from ground by way of RA235, RA241 and the lower winding of R240 to battery. Also, upon operating, the test relay R240 prepares, at RA242, the previously traced circuit for energizing the winding of the control relay R250, which circuit is completed, after a predetermined time interval, by the operation of the timing apparatus TA265 associated with the control conductor P1, thereby to cause the control relay R250 to operate as previously explained. Upon operating, the control relay R250 completes, at RA251, the previously mentioned multiple circuits for energizing the lower windings of the lockout relays in the various line circuits 20 as previously explained. At this time the lockout relay R350 in the line circuit 320 individually associated with the alarm trunk 301 completes, at RA351, upon operating, a holding circuit for energizing the upper winding thereof in series with the lower winding of the impulse relay R340. This circuit extends from ground by way of RA346, RC348, the upper winding of R350, RA351 and the lower winding of R340 to battery. When the last-mentioned circuit is completed, the lockout relay R350 is retained in its operated position and the impulse relay R340 operates. At this time only the lockout relay R350 in the line circuit 320 individually associated with the faulty alarm trunk 301 operates to complete a holding circuit for energizing the upper winding thereof in series with the associated impulse relay, due to the fact that only the associated line relay R345 occupies its restored position at this time as previously explained. Upon operating, the impulse relay R340 causes the timing relay R335 and the control relay R330 to restore as previously explained, whereupon the previously 30 traced circuits for energizing the start relay R210 and the second impulse relay R230 in the repeater 200 restore. When the start relay R210 and the second impulse relay R230 restore, the repeater 200, each of the box lines and each of the combination box and alarm lines are rendered idle. Although alarms initiated on the various box lines and on the various combination box and alarm lines are not repeated by way of the faulty alarm trunk 301 to the central office 50 at this time, these alarms are repeated by the repeater 200 over the various combination box and alarm lines. Accordingly, the signaling system is not rendered completely inoperative even though the alarm trunk 301 extending between the central office 50 and the repeater 200 at the repeater station 60 fails due to an open circuit fault thereon.

70 While there has been described what is at present considered to be the preferred embodiment of the invention, it will be understood that various modifications may be made therein, and it is intended to cover in the appended claims

all such modifications as fall within the true spirit and scope of the invention.

What is claimed is:

1. In a signaling system, a plurality of stations, a repeater, a plurality of lines respectively extending between said stations and said repeater, a sender at each of said stations operative to send a signal over the associated line, relays individually associated with said lines, each of said relays being provided with an operating circuit and a holding circuit, means for controlling the operating circuit of each of said relays in accordance with a signal sent over the associated line, thereby normally to cause the relay to operate intermittently, means controlled by the intermittent operation of any one of said relays for completing the holding circuits of the other of said relays, thereby to prevent intermittent operation of said other relays, a repeating device included in said repeater, and means for controlling said repeating device in accordance with the intermittent operation of said one relay.

2. In a signaling system, a plurality of stations, a repeater, a plurality of lines respectively extending between said stations and said repeater, an impulse sender at each of said stations operative to send impulses over the associated line, impulse relays and timing relays individually associated with said lines, each of said impulse relays being provided with an operating circuit and a holding circuit, means for controlling the operating circuit of each of said impulse relays in accordance with impulses sent over the associated line, thereby normally to cause the impulse relay to operate intermittently, means controlled by the intermittent operation of any one of said impulse relays for controlling the associated one of said timing relays, means controlled by said one timing relay for interrupting a point in the holding circuit of said one impulse relay and for completing the holding circuits of the other of said impulse relays, thereby to prevent intermittent operation of said other impulse relays, a repeating device included in said repeater, means for controlling said repeating device in accordance with the intermittent operation of said one impulse relay, and means controlled by said one timing relay after the impulses have been sent over the associated line for interrupting the holding circuits of said other impulse relays.

3. In a signaling system, a plurality of stations, a repeater, a plurality of lines respectively extending between said stations and said repeater, an impulse sender at each of said stations operative to send impulses over the associated line, impulse relays individually associated with said lines, each of said impulse relays being provided with a normally completed operating circuit and a normally interrupted holding circuit, means for controlling the operating circuit of each of said impulse relays in accordance with impulses sent over the associated line, thereby to cause the impulse relay to restore intermittently, means for interrupting the operating circuit of each of said impulse relays in the event the associated line is subjected to an open circuit fault, thereby to cause the impulse relay to remain restored, means controlled by the restoration of any one of said impulse relays for interrupting a point in the holding circuit of said one

impulse relay and for completing the holding circuits of the other of said impulse relays, thereby to prevent restoration of said other impulse relays, a repeating device included in said repeater, means for controlling said repeating device in accordance with the intermittent operation of said one impulse relay, means including a timer controlled in the event said one impulse relay remains restored a predetermined time interval for completing the holding circuit of said one impulse relay, and means controlled when the line associated with said one impulse relay is recompleted for interrupting the holding circuit of said one impulse relay.

4. In a signaling system, a plurality of stations, a repeater, a plurality of lines respectively extending between said stations and said repeater, an impulse sender at each of said stations operative to send impulses over the associated line, impulse relays and timing relays individually associated with said lines, each of said impulse relays being provided with a normally completed operating circuit and a normally interrupted holding circuit, each of said timing relays being provided with an operating circuit, means for controlling the operating circuit of each of said impulse relays in accordance with impulses sent over the associated line, thereby to cause the impulse relay to restore intermittently, means for interrupting the operating circuit of each of said impulse relays in the event the associated line is subjected to an open circuit fault, thereby to cause the impulse relay to remain restored, means controlled by the restoration of any one of said impulse relays for completing the operating circuit of the associated one of said timing relays, thereby to cause said one timing relay to operate, means controlled by the operation of said one timing relay for interrupting a point in the holding circuit of said one impulse relay and for completing the holding circuits of the other of said impulse relays, thereby to prevent restoration of said other impulse relays, a repeating device included in said repeater, means for controlling said repeating device in accordance with the intermittent operation of said one impulse relay, means controlled by the restoration of said one timing relay after the impulses have been sent over the associated line for interrupting the holding circuits of said other impulse relays, means including a timer controlled in the event said one impulse relay remains restored a predetermined time interval for completing the holding circuit of said one impulse relay, and means controlled when the line associated with said one impulse relay is recompleted for interrupting the holding circuit of said one impulse relay.

5. In a signaling system, first and second groups of signal lines, a trunk line, each signal line in said second group and said trunk line having a receiver individually associated therewith, each signal line in each of said groups having at least one sender individually associated therewith, each of said senders including normally effective means for sending a signal over the associated signal line and means governed when a signal is being sent over the associated signal line for rendering ineffective said last-mentioned means, a repeater commonly associated with each of said groups of signal lines and said trunk line, and means included in said repeater for receiv-

ing a signal sent over any signal line in said first group and for repeating the signal only over the signal lines in said second group and over said trunk line and for receiving a signal sent over any signal line in said second group and for repeating the signal only over the other signal lines in said second group and over said trunk line.

6. In a signaling system, first and second groups of signal lines, a trunk line, each signal line in said first and second groups and said trunk line having a receiver individually associated therewith, means for sending a signal over said trunk line, each signal line in said first group having at least one sender individually associated therewith, each of said senders including normally effective means for sending a signal over the associated signal line and means governed when a signal is being sent over the associated signal line for rendering ineffective said last-mentioned means, a repeater commonly associated with each of said groups of signal lines and said trunk line, and means included in said repeater for receiving a signal sent over any signal line in said first group and for repeating the signal only over the signal lines in

said second group and over said trunk line and for receiving a signal sent over said trunk line and for repeating the signal over the signal lines in said first and said second groups.

7. In a signaling system, first and second groups of signal lines, a trunk line, each signal line in said first and second groups and said trunk line having a receiver individually associated therewith, means for sending a signal over said trunk line, each signal line in said second group having at least one sender individually associated therewith, each of said senders including normally effective means for sending a signal over the associated signal line and means governed when a signal is being sent over the associated signal line for rendering ineffective said last-mentioned means, a repeater commonly associated with each of said groups of signal lines and said trunk line, and means included in said repeater for receiving a signal sent over any signal line in said second group and for repeating the signal only over the other signal lines in said second group and over said trunk line and for receiving a signal sent over said trunk line and for repeating the signal over the signal lines in said first and said second groups.
